US0D1026910S

(12) **United States Design Patent** (10) **Patent No.:** **US D1,026,910 S**
(45) **Date of Patent:** **** May 14, 2024**

(54) **DISPLAY DEVICE**

(71) Applicant: **HTC Corporation**, Taoyuan (TW)

(72) Inventors: **Shu-Kuen Chang**, Taoyuan (TW); **Natalia Amijo**, Taoyuan (TW); **Ian James McGillivray**, Taoyuan (TW); **Chin-Wei Chou**, Taoyuan (TW); **Yi-Shen Wang**, Taoyuan (TW); **Chih-Sung Fang**, Taoyuan (TW); **Hung-Yu Chen**, Taoyuan (TW)

(73) Assignee: **HTC CORPORATION**, Taoyuan (TW)

(**) Term: **15 Years**

(21) Appl. No.: **29/915,998**

(22) Filed: **Nov. 7, 2023**

(57) **CLAIM**

The ornamental design for a display device, as shown and described.

DESCRIPTION

FIG. 1 is a perspective view of a display device, such as a head mounted display, a virtual reality display, an augmented reality display, or a mixed reality display, in accordance with our new design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The broken lines immediately adjacent the claimed areas represent the bounds of the claimed design while all other broken lines are directed to environment and are for illustrative purposes only. The broken lines form no part of the claimed design.

1 Claim, 7 Drawing Sheets
